UNITED STATES PATENT OFFICE

109,782

DESIGN FOR A COMBINATION KNITTED HOOD AND SCARF

George E. Brabeck, St. Paul, Minn.

Application February 21, 1938, Serial No. 75,327

Term of patent 14 years

To all whom it may concern:

Be it known that I, George E. Brabeck, a citizen of the United States, residing in the city of St. Paul, county of Ramsey and State of Minnesota, have invented a new, original, and ornamental Design for a Combination Knitted Hood and Scarf, of which the following is a specification, reference being had to the accompanying drawing, forming a part thereof.

In the drawing, Figure 1 is a front perspective view showing my new design for a combination

knitted hood and scarf in the position for normal use, and Figure 2 is a side perspective view of the same in a display position.

The dominant feature of the design consists of the annular fold encircling the crown of the hood, as shown.

I claim:

The ornamental design for a combination knitted hood and scarf as shown and described.

GEORGE E. BRABECK.
